UNITED STATES PATENT OFFICE.

SAM FISHMAN, OF NASHVILLE, TENNESSEE.

SAFETY-BUTTON FASTENER.

1,362,786.

Specification of Letters Patent. Patented Dec. 21, 1920.

Application filed July 2, 1919. Serial No. 308,110.

To all whom it may concern:

Be it known that I, SAM FISHMAN, a citizen of the United States, residing at Nashville, in the county of Davidson and State 5 of Tennessee, have invented or discovered certain new and useful Improvements in Safety-Button Fasteners, of which the following is a specification, reference being had therein to the accompanying drawing.

10 This invention has for its object to provide a safety pin button fastener which comprises a safety pin to which the shank or eye portion of a button is attached in such a manner that the button cannot move 15 endwise of the pin, this attachment of the button to the pin being preferably at one end of the latter so that a button attached to a garment by a safety pin may be conveniently entered into or disengaged from 20 a buttonhole. To this end, in the preferred form of my invention, the wire, of which the body of the safety pin is composed, is engaged with an eye portion of a button and is then twisted so as to form a closed 25 eye in the wire of the safety pin which will hold the button from endwise movement relative to the safety pin, this closed eye being preferably at the end of the safety pin opposite to the guard or keeper with which 30 the free end of the safety pin is engaged when the pin is in closed or operative position.

In the accompanying drawing Figure 1 is a perspective view of a preferred form of 35 the invention in which the button portion of the device is provided with a metal shank having an eye, and Fig. 2 is a perspective view of a slightly different form of the invention and showing a button having an 40 eye portion which is integral with the head portion of the button. Fig. 3 shows a modified form of the invention in which a button is attached to the spring coil portion of the safety pin by a closed wire loop which 45 is independent of the wire forming the body of the safety pin.

Referring to the drawing, 12 denotes the wire body of a safety pin which is provided at one end with a guard or keeper 13 for 50 the point of the pin. The guard or keeper 13 is permanently attached to the pin 12,

or is a permanent part of said pin, the latter having, at its end opposite said guard or keeper, a spring coil which serves to retain the pointed member of the pin in the 55 guard or keeper. In the form of the invention shown in Fig. 1 the body of the safety pin is provided at its end opposite the guard or keeper with a closed loop or eye 14 which is engaged with the eye of the shank 15 of 60 a button 16, the wire of the safety pin having been passed through the eye of the said button shank before the safety pin wire had been twisted to form the closed loop or eye 14. 65

Fig. 2 shows a form of the invention similar to Fig. 1 excepting that the twisted loop or eye 14 is engaged with an eye portion 15^a integral with the button 16^a.

In the form of the invention shown in 70 Fig. 3 the button 16^b is attached to the spring coil portion 14^b of the safety pin by a fastening 17 which is preferably of wire independent of the wire of the body of the safety pin and which is engaged with the 75 said spring coil 14^b and with the eye 15^b of the button 16^b.

From the foregoing it will be understood that the invention provides a safety pin button fastener to one end of which a button is loosely or flexibly attached in such a manner that it may be readily entered into or disengaged from a buttonhole in a garment with as much facility as though the button were sewed on in an ordinary manner; while the safety pin, being readily detachable from the garment, may be placed in different positions on the garment in such a manner as to loosen or tighten the latter, as may be desired. In other words, 80 the button has a jointed connection with one end of the safety pin so that it may be freely manipulated in buttoning or unbuttoning. The invention is particularly 85 adapted for use on the collar band of a 90 shirt or other garment where changes in 95 the positions of the buttons are often desirable.

Of course it will be understood that the invention may vary from the particular 100 forms herein shown and described, and may comprise different forms of buttons than

those herein shown, as, for example, buttons having central bars instead of eyes or holes.

Having thus described my invention I claim and desire to secure by Letters Patent:

A detachable button fastener consisting of a safety pin provided at one end with a guard or keeper which is a permanent part

thereof, said pin having at its opposite end a spring coil which serves to retain the pointed member of said pin in said guard or keeper, combined with a button provided with a closed loop or eye having a jointed connection with said spring coil.

In testimony whereof I affix my signature.

SAM FISHMAN.
